UNITED STATES PATENT OFFICE.

HORACE E. DILL, OF GRANITEVILLE, SOUTH CAROLINA, ASSIGNOR TO DRAPER CORPORATION, OF HOPEDALE, MASSACHUSETTS, A CORPORATION OF MAINE.

FEELER MECHANISM FOR LOOMS.

Application filed December 18, 1921. Serial No. 523,322.

To all whom it may concern:

Be it known that I, HORACE E. DILL, a citizen of the United States, residing at Graniteville, in the county of Aiken and State of South Carolina, have invented an Improvement in Feeler Mechanisms for Looms, of which the following description, in connection with the accompanying drawings, is a specification, like characters on the drawings representing like parts.

This invention relates to feeler mechanisms for looms, wherein a fresh supply of filling is furnished when the filling in the shuttle becomes substantially exhausted.

The feeler mechanism must be sensitive either to the presence or substantial absence of filling, because should the feeler fail to indicate substantial exhaustion of filling on a detecting beat, defective cloth will result, whereas if the feeler calls for a change of filling prior to complete exhaustion, a great waste of yarn will take place, because the yarn which remains upon the filling carrier or bobbin when it is ejected from the shuttle, constitutes waste.

It sometimes happens that a filling carrier or bobbin is ejected from the shuttle while it still contains a substantial or working supply of filling, because the feeler may not accurately perform its detecting function, and the amount of waste thus produced constitutes a great objection to some types of feeler mechanisms.

An important feature of the present invention, therefore, consists of a feeler mechanism having a replenishing preventer which prevents the call for replenishment by the feeler provided a working supply of filling still remains within the shuttle, but permits the functional operation of the feeler to call the change, should the filling be substantially exhausted.

The above and other features of the present invention and novel combination of parts will be made clear from the following description and accompanying drawings of one embodiment of the invention.

In the drawings:—

Figure 1 is a perspective view showing one form of feeler mechanism containing the present invention, and illustrating the operation when a working supply of filling is present in the shuttle; and

Fig. 2 is a view similar to that of Fig. 1, showing the operation of the mechanism

when the filling is substantially exhausted on a detecting beat.

The filling replenishing mechanism and the train of devices between the feeler mechanism and the replenishing mechanism for initiating the operation of the latter through the feeler are now well understood, and consequently these features have not been shown and will not be herein described, it being understood that the transferring mechanism as well as the train of devices between the feeler and said mechanism for initiating the operation thereof may be of usual or any preferred type.

In the present instance the feeler is shown as of the general character of the feeler mechanism shown, described and claimed in the patent to Edward S. Stimpson, No. 1,309,226, wherein the feeler is supported to enter the shuttle on each detecting beat in a direction inclined to the longitudinal axis of the shuttle, so that the forward pressure upon the feeler may cause the latter to be moved along the filling carrier or bobbin when the filling is substantially exhausted. The advantages of the present invention are clearly manifested in connection with the Stimpson type of feeler mechanism, but of course the invention may be employed in other types of feeler mechanisms, and its advantages be realized in connection therewith.

The feeler stand 1 is adjustably secured to the supporting bracket 2 by means such as the bolt 3 which passes through a slot 4 in the feeler stand. Mounted in a suitable guideway 5 at the rear portion of the feeler stand 1 is a controller 6 which is constituted as a laterally-movable slide having a slotted portion 7 through which the feeler 8 extends. The controller 6 is connected to a transmitter 9 which is itself connected to the train of mechanism for effecting replenishment of filling when the controller or slide 6 is moved laterally or in a direction longitudinally of the shuttle. A cover plate 10 is secured to the rear portion of the feeler stand by securing means such as the screws or bolts 11 and forms a convenient means for retaining the controller or slide 6 in its guide 5 and free for lateral movement therein.

The feeler 8 in the present instance is connected to a bridge 12 and extends forwardly through a swiveled block 13, between

which and the bridge 12 is the spring 14 normally acting to move the feeler into its rearward feeling position.

The parts thus far described are substantially the same as the similar parts in the Stimpson patent hereinbefore mentioned, and for a more full disclosure and description thereof, reference may be had thereto.

On each detecting beat of the lay, the 10 feeler is moved frontwardly by engagement with the surface within the shuttle, and when a working supply of filling is present in the shuttle on a detecting beat, the rear toothed end portion 15 of the feeler will 15 sink more or less into the filling mass 16, Fig. 1, and ordinarily be held from movement along the filling carrier or bobbin as the lay beats up. The bobbin 17 has the usual head 18 provided with the holding 20 rings 19, whereby the bobbin is retained within the shuttle. These parts, as well as the shuttle, are well known and understood at the present time, and for further amplification thereof, reference may be had to the 25 Stimpson patent hereinbefore mentioned.

When the filling is substantially exhausted on a detecting beat, the toothed end portion 15 of the feeler will no longer be held from movement in a direction longitudinally of the shuttle by the small amount of filling still remaining on the filling carrier or bobbin, as indicated in Fig. 2, and the movement of the feeler for calling a change of filling will be effected.

It happens at times, however, that the 30 rear end portion of the feeler fails to be held by the filling, even when a working supply of filling is present in the shuttle on a detecting beat, and in such case replenishment of filling will be effected even though a working supply of filling still remains upon the filling carrier or bobbin. The waste incident to this defective action is considerable, and it is important that the 35 feeler be prevented from improperly indicating for a change of filling when a working supply of filling is present in the shuttle.

In the present instance the feeler 8 has a projection 20 which, when the feeler is engaged by a working mass of filling in the shuttle, as the lay moves frontwardly, is engaged at one side of a finger as the feeler moves frontwardly, so that as the pressure of the filling increases, and the tendency 45 of the feeler to move longitudinally of the shuttle becomes more pronounced, the replenishing preventer acts to prevent the feeler from responding to its tendency for movement longitudinally of the shuttle to 50 thereby call the change.

In the present instance the feeler stand 55 has extending rearwardly therefrom the preventer finger 21 which is adjustably secured by a screw 22 or other securing means, to 60 the feeler stand. As shown, the finger 21

has its front portion slotted as at 23 so that by loosening the screw 22, the finger 21 constituting a part of the preventer, may be adjusted rearwardly or forwardly to properly locate it and the projection extending 70 from the feeler so that when a working supply of filling is present in the shuttle, the projection 20 will pass to one side of the finger 21, (to the left in the present instance) as the feeler is pushed frontwardly 75 by the filling mass; but when the filling has become substantially exhausted and the lay starts frontwardly, the teeth 15 on the rear portion of the feeler will respond to the frontward pressure of the now substantially-denuded bobbin or filling carrier, and will slip or slide longitudinally thereof as indicated in Fig. 2, so that the projection 20 will pass to the opposite side of the finger 80 and the feeler will be free to call the change. 85

The finger 21 is preferably formed with its rear end portion 24 pointed or shaped in such manner that as the feeler moves frontwardly under the frontward pressure of a working mass of filling, the projection 90 20 will ride along the rear curved end portion of the finger and prevent movement of the feeler longitudinally of the shuttle; but when, on a detecting beat, the filling is substantially exhausted, the longitudinal movement 95 of the feeler will be effected by the frontward pressure as indicated in Fig. 2, before the projection 20 reaches the finger on the frontward movement of the feeler, with the result that the projection 20 will 100 pass to the opposite side or to the right of the finger 21 and filling replenishment will be called.

The projection 20 is shown as a metal piece or wire secured to the feeler 8 rearward of the feeler stand, and it is provided with an upturned portion 25 which constitutes a part of the projection that rides along the finger 21. The finger 21 is preferably formed also as a metal piece adjacent 105 the position of the feeler, and coacts with the projection 20 to prevent movement of the feeler to call a change of filling when there still remains sufficient filling in the shuttle for weaving purposes, but permits 110 such movement when the filling is substantially exhausted on a detecting beat.

What is claimed is:—

1. In a loom having a feeler mechanism, comprising, in combination, a feeler supported in a position and for normal movement inclined to the longitudinal axis of the shuttle on each detecting beat and for abnormal movement at an increased inclination to effect replenishment of filling when the filling is substantially exhausted, a projection carried by the feeler, and a preventer finger mounted in fixed position and to one side of which the projection passes in its normal inclined movement with a work- 120 125 130

- ing supply of filling in the shuttle on a detecting beat, and to the other side of which the projection passes when the feeler partakes of its abnormal inclined front-
5 ward movement upon substantial exhaustion of filling.
2. A loom having a feeler mechanism, comprising, in combination, a feeler support secured in fixed position, a feeler that
10 is mounted to slide in a normally inclined direction towards and from the front of the loom on said support on each detecting beat and to slide on said support in an abnor-
mally inclined direction when the filling
15 is substantially exhausted, a finger secured to the fixed support, and a projection carried by the feeler which is moved in an inclined direction frontwardly to pass at one side of the finger on the fixed support during nor-
20 mal movement of the feeler and to the op-
posite side of said finger when the feeler partakes of its abnormal inclined movement.
3. In a feeler mechanism for looms, the
25 combination of a feeler stand, a feeler mounted for movement in a direction longi-
tudinally of the shuttle and normally re-
strained from such movement on a detect-
ing beat by engagement with the filling until
30 substantial exhaustion thereof, means for
replenishing the filling when the feeler par-
takes of its longitudinal movement on a
detecting beat, a replenishing preventer
35 comprising a member secured in fixed posi-
tion and having its end extending rear-
wardly from the feeler stand, and a pro-
jection connected to the feeler back of the
feeler stand and engaging at one side of the
40 said member when the lay beats up on a
detecting beat with a working supply of
filling in the shuttle and passing to the other
side of said member when the filling is sub-
stantially exhausted on a detecting beat.
4. In a feeler mechanism for looms, the
45 combination of a feeler that is supported to
enter the shuttle in a direction inclined to
the longitudinal axis of the shuttle and for
movement along the filling carrier by the
frontward pressure on a detecting beat to
50 effect replenishment of filling, a finger mount-
ed in fixed position at the front of the loom
and extending rearwardly towards the lay,
and a projection carried by the feeler and
adapted to engage the said finger and pre-
55 vent premature replenishment of filling
when a working supply is present in the
shuttle on a detecting beat.
5. In a feeler mechanism for looms, the
combination of a feeler stand secured in
fixed position, a feeler mounted directly
upon the feeler stand to enter the shuttle
60 in a direction inclined to the longitudinal
axis thereof and displaced frontwardly in
an inclined direction by the frontward pres-
sure on a detecting beat, a projection se-
cured to the feeler, a replenishing preventer
65 comprising a rearwardly extended finger to
one side of which the projection on the
feeler passes as the feeler is moved in its
inclined direction frontwardly when a work-
ing supply of filling is in the shuttle on
70 a detecting beat and to the other side of
which it passes when the filling is substan-
tially exhausted.
6. In a feeler mechanism for looms, the
combination of an inclined feeler, a feeler
75 stand, a finger adjustably mounted on the
feeler stand and having a tapered end por-
tion and a projection on the feeler which
passes to one side of the tapered end portion
of the finger as the feeler is moved in an
80 inclined direction frontwardly by a work-
ing supply of filling and to the other side
of the finger when the filling is substantially
exhausted.

In testimony whereof, I have signed my
name to this specification.

HORACE E. DILL.
